UNITED STATES PATENT OFFICE

LOTHAR WILHELM MAYER AND PAUL RICKARD WETZEL, OF CHICAGO, ILLINOIS

GLAZIER'S POINT SETTER

Application filed June 30, 1928. Serial No. 289,497.

This invention relates to a glazier's point setter, and it is an object of the invention to provide a device of this kind wherein the desired power to operate the setter is so equalized as to minimize the liability of the device jerking or jumping when in use and thus preventing breakage of the glass.

Another object of the invention is to provide a device of this kind embodying a hammer together with means whereby the extent of the stroke of the hammer may be lengthened or shortened as the requirements of practice may prefer.

The invention also has for an object to provide a point setter of this kind which, when in use, does not have to be clamped into working position and which includes a hammer adapted to be manually retracted and which is released for its striking or impact stroke through the medium of a trigger.

A still further object of the invention is to provide a device of this kind including a magazine and a hammer having requisite movement with respect to the magazine together with means whereby is assured the delivery of only a single point into position for impact by the hammer.

The invention consists in the details of construction and in the combination and arrangement of the several parts of our improved glazier's point setter whereby certain important advantages are attained and the device rendered simpler, less expensive and otherwise more convenient and advantageous for use, as will be hereinafter more fully set forth.

The novel features of our invention will hereinafter be definitely claimed.

In order that our invention may be the better understood, we will now proceed to describe the same with reference to the accompanying drawings, wherein:

Figure 1 is a view partly in vertical section and partly in elevation illustrating a glazier's point setter constructed in accordance with an embodiment of our invention;

Figure 2 is a sectional view taken substantially on the line 2-2 of Figure 1, looking in the direction of the arrows;

Figure 3 is a view in front elevation of the device as illustrated in Figure 1;

Figure 4 is a view in bottom plan of the magazine plate as herein employed;

Figure 4^a is a view in edge elevation of the plate illustrated in Figure 4;

Figure 5 is a view in plan of the driver guides and plate unapplied;

Figure 5^a is a view in front elevation of the structure as illustrated in Figure 5;

Figure 6 is a view in elevation of an adjustment plate for use in connection with the magazine;

Figure 6^a is a view in bottom plan of the plate illustrated in Figure 6;

Figure 7 is a view similar to Figure 1 but showing certain of the parts in different positions;

Figure 8 is a view in side elevation of the hammer and the parts directly associated therewith as herein disclosed;

Figure 8^a is a view in front elevation of the structure as illustrated in Figure 8;

Figure 9 is a view in front elevation of the trigger as herein employed unapplied;

Figure 9^a is a view in side elevation of the trigger as illustrated in Figure 9;

Figure 10 is a fragmentary view in front elevation of the lower portion of the magazine and the magazine plate associated therewith.

As disclosed in the accompanying drawings, F denotes the frame of the device and which is substantially in the form of an inverted U with one end member or leg 8 substantially straight from end to end and the opposite or second end member or leg 33 formed after the fashion of a pistol grip adapted to be grasped by the hand of the user. The members or legs 8 and 33 together with the intermediate portion of the frame have their longitudinal marginal portions defined by the inwardly disposed flanges 1 whereby the frame F also constitutes what may be called a "housing". Pivots connected, as at 25, between the flanges 1, preferably by outstanding trunnions, is the upper end portion of a lever 9.

The pivotal connection 25 is closely adjacent to the upper end portion of the member 100

or leg 8 of the frame F and the lever 9 is disposed in a general direction toward the opposite end of the member or leg 8. The pivoted end portion of the lever 9 is continued by an elongated arm 2 arranged between the side flanges 1 disposed along the intermediate portion 3 of the frame F and terminates closely adjacent to the second member or leg 33. The free end portion of the arm 2 is continued by the downwardly disposed extension 4, the inner edge 4' of which being arranged on a downward and outward incline.

A trigger 10 is pivotally supported, as at 23, between the flanges 1 at the junction of the intermediate portion or member 3 of the frame F and the member or leg 33 and at points in advance of the extension 4 but below the arm 2. The pivoted end portion of the trigger 10 is bifurcated to provide spaced arms 5, each of which having associated therewith a pivotal mounting 23, such as a screw or the like.

The arm 2 in its swinging movement in connection with the lever 9 is adapted to swing between the arms 5 and said arms of such length to permit the arm 2 and lever 9 to have desired swinging action.

The free end portion of the extension 4 has secured thereto an end portion of a retractile coil spring 20, the opposite end portion of which being suitably anchored, as at 34, to a lower portion of the member or leg 33, and more particularly the flanges 1 thereof. This spring 20 serves to constantly urge the arm 2 downwardly and the lever 9 in a direction toward the member or leg 8, yet permits the same to readily have swinging movement in the opposite direction.

The movements of the arm 2 and lever 9 are under control of the lever 10 and which lever at a point closely adjacent to the arms 5 thereof is provided with a rearwardly disposed and upwardly curved pin 22, the free end portion of which having contact with the inclined edge 4' of the extension 4. In practice, the fingers of the hand grasping the member or leg 33 may be readily used to impose requisite pull upon the trigger 10 to force the arm 2 upwardly and the lever 9 rearwardly for a purpose to be hereinafter more particularly referred to.

The member or leg 8 of the frame F also constitutes a magazine for holding a supply of points and the chamber of said magazine 32 is triangular in cross section to conform to the configuration of said points and said magazine is open at opposite ends.

The cross sectional configuration of the chamber of the magazine 32 is preferably of such dimensions to receive a stack of points of the maximum size. When it is desired to employ points of smaller sizes an elongated plate 6 of desired thickness is inserted from above within the chamber of the maga-

zine in close contact with the posterior wall of the chamber of the magazine. The upper end portion of such plate 6 is provided with an enlargement or head 6' to facilitate its application or removal, it being understood that when the plate 6 is applied said enlargement or head 6' will be disposed above the upper open end of the chamber of the magazine. It is also preferred that the points when applied within the chamber of the magazine 32 be arranged in a symmetrical column with adjacent points lightly connected by suitable adhesive.

Underlying the lower end of the magazine 32 and member or leg 8 is a magazine plate 13 maintained in applied or working position through the medium of the rivets 26 or the like. The forward portion of the plate 13 is provided with a triangular opening 13' which is in register with the lower end of the chamber of the magazine 32 and through which the points within the chamber of the magazine 32 are adapted to pass by gravity for successive position in desired alignment with the driver plate 15. The driver plate 15 underlies the applied magazine plate 13 for close contact therewith and the side marginal portions of the plate 15 have secured thereto by the rivets 27 or the like the forward end portions of the driver guide members 14. Interposed between the overlying portions of the guide members 14 and the plate 15 are the spacer strips 16 maintained in desired position through the medium of the rivets 27 or the like hereinbefore referred to. These guide members 14 extend rearwardly of the driver plate 15 and are received within the rabbets 7 provided in the lower side marginal portions of the base portion of a driver block 11. These extended portions of the members 14 are anchored to the base portion of the driver block 11 through the medium of rivets 36 or the like. It is to be noted that the outer side faces and the bottom faces of the extended portions of the members 14 received within the rabbets 7 are flush with the side and under faces of the bottom portion of the driver block 11.

The lower portion of the member 8 is laterally extended in opposite directions, as at 8', as particularly illustrated in Figure 10 and said extensions are provided with the bearing grooves or channels 37 open from below and which receive the forward portions of the members 14, or those portions of said members in advance of the driver block 11. The side marginal portions of the applied magazine plate partially underlie said grooves or channels 37 and the members 14 received therein whereby said members 14 are effectively maintained for sliding movement within the grooves or channels 37. Extending rearwardly from the central part of the lower portion of the driver block 11 is 130

- an elongated rod or shank R, the outer or free end portion of which at all times being slidably and snugly received within an opening 33' provided in the lower or free 5 end portion of the member or leg 33. This opening 33' is continued through a wooden block 21 secured to the member or leg 33 by the screws 24, said block projecting beyond opposite sides of the member or leg 33 to provide an increased bearing surface. As particularly illustrated in Figures 1 and 7, it is to be noted that the under face of this applied block 21 is flush with the adjacent free end of the member or leg 33.
- 10 Surrounding the rod or shank R and interposed between the lower portion of the driver block 11 and the lower or free end portion of the member or leg 33 is a spring 17 which, upon rearward movement of the driver block 20 11, is placed under compression to provide means to impart the requisite striking or impact stroke to the driver block 11.
- 15 The lower portion of the driver block 11 is also provided with the oppositely disposed 25 and laterally directed pins 35 with each of which is engaged an end portion of a retractile spring 18, the opposite end portion of said spring being secured to an extended portion 8' of the member or leg 8. As the driver 30 block 11 is retracted both of the springs 18 are placed under tension to facilitate the desired striking or impact stroke of the block.
- 20 The driver block 11 extends within the frame F a desired distance and its upper portion is provided with a groove or channel 11' of desired depth and extending in the same general direction as the path of travel of the block 11. Pivotaly mounted intermediate its ends, as at 28, within the groove or channel 11' is an elongated member or plate 12. The forward end portion of the plate 12 extends in advance of the driver block 11 and has contacting therewith from below the free end portion of a leaf spring 19, the opposite 40 end portion of which being secured, as at 29, by a rivet or the like to the forward face of the block 11. This spring 19 serves to constantly urge the extended or forward end portion of the member or plate 12 upwardly, the extent of such movement being limited by a set screw 30 threaded through the opposite or rear end portion of the member or plate 12 and adapted to have contact with the face of the groove or channel 11'. 50 31 denotes a lock nut engaged with the set screw 30 and contacting with the adjacent portion of the member or plate 12 to effectively hold the set screw 30 in its desired endwise adjustment.
- 55 When the driver block 11 is at the limit of its forward movement the extended end of the plate or member 12 is closely adjacent to the lower or free end portion of the lever 9 with said lever 9 extending below the upper 60 surface of said end of the plate or member 12

as determined by the swinging adjustment of the plate or member 12 about its pivot 28 through the instrumentality of the set screw 30.

As the trigger 10 is drawn toward the member or leg 33 the pistol, as it has been termed, or free end portion of the lever 9 will come in contact with the adjacent end of the member or plate 12 and force the driver block 11 rearwardly until the lever 9 passes upwardly 70 out of contact with the adjacent end of the member or plate 12. At this time the springs 17 and 19 hereinbefore referred to will cause the driver block 11 to move toward the member or leg 8 with sufficient speed to permit the driver plate 15 to have requisite impact from the rear upon the point projected through the opening 13' in the magazine plate 13 and in alignment with the plate 15. This action results in such point being driven 75 within a window sash or the like in proper relation with respect to the glass pane. The extent of retraction of the driver block 11 by the lever 9 is regulated or controlled by the extent of adjustment of the member or plate 20 12 about its pivot 28. The lower the front 80 end of the member or plate 12 the shorter the stroke of the block 11 and vice versa.

The arrangement of the member or leg 33 or grip, as it may be termed, together with the springs 17 and 18 results in an effective equalization of the power and in a manner to keep the device from jerking or jumping during a working operation and thus preventing breakage of glass.

It is also to be particularly noted that the device is of such a construction that makes it extremely light and which in connection with a device of this kind is an important factor. It is also to be noted that the mounting 90 of the driver block 11 is such as to possess a maximum of strength and that the assembly of such block 11 when in working position eliminates liability of the driver plate 15 bending or getting out of place and which decided advantage is particularly due to the guide springs 14 and the parts directly associated therewith.

From the foregoing description it is 100 thought to be obvious that a glazier's point setter constructed in accordance with our invention is particularly well adapted for use by reason of the convenience and facility with which it may be assembled and operated, and it will also be obvious that our invention is 110 susceptible of some change and modification without departing from the principles and spirit thereof and for this reason we do not wish to be understood as limiting ourselves to the precise arrangement and formation of the several parts herein shown in carrying out our invention in practice except as hereinabove claimed.

We claim:

1. A glazier's point setter comprising a 130

substantially U-shaped frame, one leg of which being formed to provide a magazine and the second a hand grip, a plate secured to the working end of the leg provided with the magazine and having an opening registering with the discharge end of the magazine chamber, said leg at opposite sides of the chamber being provided with channels, said applied magazine plate partially underlying said channels, elongated guide members movable through said channels and held therein by the extended portions of the magazine plate, a driver plate secured to and bridging the space between the forward end portions of the guide members, said driver plate underlying the magazine plate, a driver block, means for securing the inner portions of the guide members to the driver block, means for retracting the driver block, and means for imparting an impact stroke to the driver block upon release therefrom of the retracting means.

2. A glazier's point setter comprising a substantially U-shaped frame, one leg of which being formed to provide a magazine and the second a hand grip, a plate secured to the working end of the leg provided with the magazine and having an opening registering with the discharge end of the magazine chamber, said leg at opposite sides of the chamber being provided with channels, said applied magazine plate partially underlying said channels, elongated guide members movable through said channels and held therein by the extended portions of the magazine plate, a driver plate secured to and bridging the space between the forward end portions of the guide members, said driver plate underlying the magazine plate, a driver block, means for securing the inner portions of the guide members to the driver block, means for retracting the driver block, retractile springs secured to the driver block and to the leg provided with the magazine and placed under tension upon retraction of the driver block, and a compression spring interposed between the driver block and the second leg of the frame and placed under compression upon retraction of the driver block, said springs imparting the impact stroke to the driver block upon release of the retracting means from the driver block.

3. A glazier's point setter comprising a substantially U-shaped frame, one leg of which being formed to provide a magazine and the second a hand grip, a plate secured to the working end of the leg provided with the magazine and having an opening registering with the discharge end of the magazine chamber, said leg at opposite sides of the chamber being provided with channels, said applied magazine plate partially underlying said channels, elongated guide members movable through said channels and held therein by the extended portions of the mag-

azine plate, a driver plate secured to and bridging the space between the forward end portions of the guide members, said driver plate underlying the magazine plate, a driver block, means for securing the inner portions of the guide members to the driver block, means for retracting the driver block, means for imparting an impact stroke to the driver block upon release therefrom of the retracting means, the means for retracting the driver block comprising a lever having its upper portion pivotally engaged to the frame at a point adjacent to the upper portion of the leg provided with the magazine, said lever extending downwardly with its lower free end portion adapted to have operative engagement with the driver block, an arm carried by the pivoted portion of the lever and extending toward the second leg of the frame, said arm terminating in a depending extension, a trigger positioned adjacent to the second leg and having one end portion pivotally connected to the frame adjacent the upper portion of the second leg, said trigger being arranged below the arm and inwardly of the extension, a retractile member connected to the extension and to the second leg of the frame at a point below the extension, and an outstanding pin carried by the trigger for contact with the extension, movement of the trigger toward the second leg resulting in upward movement of the arm and inward movement of the lever to retract the driver block.

4. A glazier's point setter comprising a substantially U-shaped frame, one leg of which being formed to provide a magazine and the second a hand grip, a plate secured to the working end of the leg provided with the magazine and having an opening registering with the discharge end of the magazine chamber, said leg at opposite sides of the chamber being provided with channels, said applied magazine plate partially underlying said channels, elongated guide members movable through said channels, and held therein by the extended portions of the magazine plate, a driver plate secured to and bridging the space between the forward end portions of the guide members, said driver plate underlying the magazine plate, a driver block, means for securing the inner portions of the guide members to the driver block, means for retracting the driver block, retractile springs secured to the driver block and to the leg provided with the magazine and placed under tension upon retraction of the driver block, and a compression spring interposed between the driver block and the second leg of the frame and placed under compression upon retraction of the driver block, said springs imparting the impact stroke to the driver block upon release of the retracting means from the driver block.

5. A glazier's point setter comprising a substantially U-shaped frame, one leg of which being formed to provide a magazine and the second a hand grip, a plate secured to the working end of the leg provided with the magazine and having an opening registering with the discharge end of the magazine chamber, said leg at opposite sides of the chamber being provided with channels, said applied magazine plate partially underlying said channels, elongated guide members movable through said channels and held therein by the extended portions of the magazine plate, a driver plate secured to and bridging the space between the forward end portions of the guide members, said driver plate underlying the magazine plate, a driver block, means for securing the inner portions of the guide members to the driver block, means for retracting the driver block, means for imparting an impact stroke to the driver block upon release therefrom of the retracting means, the means for retracting the driver block comprising a depending lever pivotally connected with the upper portion of the frame, the upper face of the block having a channel extending in the same general direction as the direction of movement of the block, a plate pivotally engaged intermediate its ends to the block with a portion of the plate being received within the chan-

nel, and a second portion projecting beyond the block and toward the lower free end of the lever, said lever when swung inwardly having contact with the adjacent end of the plate to retract the driver block until the lever passes free of the plate, means for imparting swinging movement to the lever, means for constantly urging the extended portion of the plate upwardly, and means carried by the plate and coacting with the driver block for limiting said upward movement of the plate.

In testimony whereof we hereunto affix our signatures.
